KARL OTTO KELLER, OF SUNDERLAND, ENGLAND, ASSIGNOR OF ONE-HALF TO
ROBERT PILE DOXFORD, OF SUNDERLAND, DURHAM, ENGLAND.

RECIPROCATING PUMP AND THE LIKE.

1,385,005.

Specification of Letters Patent. Patented July 19, 1921.

Application filed January 6, 1921. Serial No. 435,354.

To all whom it may concern:

Be it known that I, KARL OTTO KELLER, citizen of the Swiss Confederation, of Pallion Yard, Sunderland, in the county of 5 Durham, England, have invented certain new and useful Improvements in Reciprocating Pumps and the like, of which the following is a specification.

This invention is for improvements in 10 or relating to reciprocating pumps and the like, and has for its object to provide an improved construction of driving-mechanism for operating the ram or plunger in a reciprocating pump. The invention is 15 particularly applicable to pumps which are required to work under a high pressure, such for example, as the fuel pumps of internal combustion engines.

One of the difficulties with reciprocating 20 pumps is the prevention of leakage past the ram, due either to want of alinement of the ram in its cylinder, or to wear taking place. When working against low pressures, say up to 1,000 lbs., per square inch, 25 this difficulty can be obviated by the use of packing-glands, as they can be rendered tight without causing too much friction, and the particles which are rubbed off the packing material and find their way into the 30 fuel-oil do not seriously interfere with the spraying devices used in engines working with these low fuel pressures. The case, however, is different when pressure of 10,000 lbs. per square inch or more are desirable. 35 A gland on the ram is not practicable owing to the friction resulting from making the gland tight against the high pressure, which friction causes heating of the ram. Moreover, the particles which become detached from the packing material seriously 40 obstruct the fine passages of the fuel-spraying device, such for example, as is described in our patent specification No. 394682 filed 8th July, 1920.

45 We have found it practicable to machine a ram and its cylinder or sleeve so accurately that the leakage of oil under pressure up to 12,000 lbs. per square inch is negligible under a static test, and the object of this 50 invention is to provide driving mechanism

for a ram which shall eliminate as far as possible, by elimination of side thrust on the ram, all wear which would lead to leakage.

We have heretofore used a driving connection for a ram or plunger comprising 55 a member which slides in a guide parallel or coaxial with the axis of the ram and engages it by a face which is perpendicular to the direction in which they move; this 60 face permits relative sliding movement of the driving member and the ram in the said plane perpendicular to the direction in which they reciprocate, the object of this arrangement being to insure that any 65 displacement of the driving member from its original coaxial position shall not cause the ram to be tilted out of its original position.

According to this invention, in a reciprocating pump comprising a driving member 70 which exerts thrust that may be other than coaxial with the ram of the pump, and a cross-head joined to the pump-ram by a sliding-joint between that cross-head and 75 ram in a plane perpendicular to the direction in which the ram reciprocates, there is employed a first cross-head which is connected to the cross-head of the ram by a thrust-connection interposed between the 80 two cross-heads and either connected to each of the cross-heads at its ends, for the purpose described, by pin-joints with their axes transverse to the direction in which it reciprocates, or having sliding-joints with 85 either or both of the cross-heads, which joints, like that between the ram and its cross-head, are free to permit sliding movement in a plane perpendicular to the direction in which the cross-heads reciprocate. 90

In the accompanying drawings,

Figure 1 shows more or less diagrammatically one construction of driving gear for a pump, in longitudinal section;

Fig. 2 shows a detail thereof on a larger 95 scale, and

Fig. 3 shows a modified construction.

Like reference characters indicate like parts throughout the drawings.

Referring to Fig. 1, a pump comprises a 100

ram 10 reciprocating in a sleeve 11, these two parts being machined initially with such accuracy that the leakage at the desired working pressures is negligible. The pump 5 chamber is indicated at 12.

The primary driving member of this pump, which may be of any desired kind, is usually one which introduces a lateral thrust as well as the axial thrust which is required on the ram. As illustrated, the 10 primary driving member is a connecting-rod 13 operated by a crank or eccentric 14. The other end 15 of this connecting-rod is mounted in a cross-head 16 which is free 15 to slide in a guide 17, and this guide is originally made with its longitudinal axis parallel with and preferably coaxial with the axis of the ram 10. The cross-head 16 absorbs all the lateral thrust introduced by 20 the obliquity of the driving member 13, and it transmits only a thrust which is initially coaxial with the ram. But when wear of the guide 17 and cross-head 16 takes place, the line of movement of the cross-head is 25 no longer coaxial with the ram, and the transmitted thrust may be not coaxial with the ram. There is, therefore, provided a second cross-head 18 which slides in a guide 19, this guide being (like the 30 guide 17) initially machined with its axis parallel with, and preferably coaxial with the axis of the ram.

The two cross-heads are connected by a thrust-member 20 which is connected to 35 either of them or both of them by a joint which permits displacement of the cross-head relatively to the thrust-member in a direction at right-angles to their line of movement. Such a joint is illustrated in 40 Fig. 2 in which the cross-head 16 is provided at its end with a flat face 21 which is accurately perpendicular to the longitudinal axis of the cross-head. The thrust-member 20 is formed with a corresponding flat face 45 22 which bears on the face 21 and is perpendicular to the axis of the thrust-member. The two parts are held in contact by a nut-like member 23 screwed on to the cross-head 16 and engaging by an inwardly-directed 50 flange 24 a shoulder on the member 20 which faces away from the cross-head. The flange 24 is so proportioned as to allow a certain amount of lateral movement of the cross-head 16 and nut 23 relatively to the thrust-member 20. With this construction, if the 55 cross-head 16, due to wear of its guides 17 moves along a line displaced laterally from the original line of movement, no tilt is imparted to the member 20 because the face 21 60 slides freely across the co-operating face 22 of the thrust-member 20 so that the latter maintains its original axial position.

The only possibility of a non-axial thrust being imparted to the thrust-member 20 65 arises if the guide 17 is worn to a curve,

so that the end face 21 of the cross-head becomes tilted and does not lie flat against the end face 22 of the thrust-member 20. In this case the thrust might be applied to the member 20 to one side of its longitudinal 70 axis.

It will be appreciated that any lateral thrust thus introduced by eccentricity or obliquity of the thrust transmitted from the cross-head 16 can only be small, and it is 75 absorbed by the second cross-head 18. Any wear caused by this side-thrust will be very small compared with the wear of the cross-head 16 and guide 17. The ram 10 is connected to the cross-head 18 by a joint similar to that illustrated in Fig. 2, so that even 80 the slight wear and lack of alinement which may in time arise on the cross-head 18 is not imparted to the ram 10, and the latter maintains its initial accurate fit and oil- 85 tightness in the sleeve 11.

While the construction illustrated in Fig. 1 is the preferred one, similar advantages may be obtained by a construction such as is illustrated in Fig. 3, wherein the thrust-member 20 is connected to the cross-heads 16 and 18 respectively by pin-joints 25 which are arranged with their axes transverse to the direction in which the reciprocation of the parts takes place. With this construction 95 the displacement of the cross-head 16 from its initial alinement will impart a slight tilt to the thrust-member 20; the thrust imparted to the member 18 will thereby be very slightly oblique, and the lateral component will be absorbed by the cross-head 18 causing wear thereof which is, as before, very small compared with the wear of the cross-head 16. The joint between the cross-head 18 and the ram 10 is of the 100 same type as in Fig. 1 so that even the small amount of wear between the cross-head 18 and its guide 19 does not cause any appreciable lateral thrust on the ram 10.

It is to be understood that this invention 110 is not limited to the particular driving mechanism comprising an eccentric and connecting-rod illustrated in Figs. 1 and 3, but that the hereinbefore-described arrangement of two cross-heads and guides may be interposed between any form of driving member and the ram of the pump.

What I claim as my invention and desire to secure by Letters Patent is:—

1. In a machine of the character described, 120 the combination of an oscillating and reciprocating driving member, a ram, a plurality of cross-heads between said driving member and said ram and connecting the same so as to permit relative adjusting movement between any connected pair of said elements in 125 a direction transversely of the line of reciprocation of said ram, substantially as described.

2. In a machine of the character described, 130

the combination of an oscillating and reciprocating driving member, a ram, a plurality of cross-heads between said driving member and said ram, and means connecting one of
5 said cross-heads to the ram, said means being adjustably movable relatively to the ram transversely of the line of reciprocation of said ram, and means connecting said cross-heads together and permitting relative ad-
justing movement between them in a direc- 10
tion transversely of their line of reciprocation, substantially as described.

In testimony whereof I affix my signature.

KARL OTTO KELLER.
